UNITED STATES PATENT OFFICE.

ABRAM A. STILL, OF ANNENETTE, CALIFORNIA.

GATE-CLOSER.

1,194,897.

Specification of Letters Patent. Patented Aug. 15, 1916.

Application filed April 15, 1916. Serial No. 92,519.

To all whom it may concern:

Be it known that I, ABRAM A. STILL, a citizen of the United States, residing at Annette, in the county of Kern and State 5 of California, have made an Improvement in Gate-Closers, of which the following is a specification.

My invention is an improvement in the class of devices which are adapted to close 10 a laterally swinging gate automatically when the gate is released by the person operating it.

The closing apparatus is constructed and operated as hereinafter described and illustrated in the accompanying drawing, in which:—

Figure 1 is in part a side view and in part a section showing the preferred form of my invention applied to a swinging gate. Fig. 20 2 is a plan view of the same. Fig. 3 is a plan view of a modification, a portion being in section to show interior construction.

As shown in Fig. 1, a gate F is hinged to a vertical post H and is adapted to swing 25 horizontally in either direction. The gate is provided with a spring catch which engages a catch on the opposite post.

A tube G is inserted horizontally through the top portion of the post and 30 fixed therein, while a larger and shorter tubular section G' is screwed upon the outer end of tube G. A spool or pulley C is mounted on a horizontal axis in the outer end of a larger tube G'. The inner end of 35 the longer tube is slotted horizontally, and the divided portions are flattened and two spools or pulleys D are mounted on vertical axes in such portion of the tube, the same being separated from each other by a narrow space.

A cord B is attached to a screw-eye E fixed on the top bar of the gate F, and passes thence between the spools D and through the pulley sections G and G', and 45 over the pulley C, from which it is pendent, and supports a weight A.

It is apparent that the tension applied to the cord by the weight holds the gate normally in closed position, as shown in Fig. 1, that is to say, in alinement with the two 50 posts; and that when the gate is pushed open, in either direction, the cord is drawn over the pulleys C and D, and the weight A raised correspondingly; and that, upon release of the gate, it swings automatically 55 back to its normal position by the effect of gravity applied through the medium of the weight A.

In a modification shown in Fig. 3, H' indicates a tubular post to the side of which 60 tubes G, G', with attached pulleys C and D, are secured by a screw clamp.

I. claim:—

1. The combination, with a post and a gate hinged thereto and adapted to swing laterally in either direction, of a horizontal support secured to the post and extending in opposite directions therefrom, the outer end of said support being provided with a horizontal pulley, and the inner end with 65 two vertical pulleys arranged side by side, and a weighted cord running on the outer pulley and between the inner pulleys, and attached to the top portion of the gate, as described.

75 2. The combination, with a post and a gate hinged thereto and adapted to swing in either direction, of a tubular support passing through, and fixed in, the said post, and having a horizontal pulley in its outer end, 80 its inner end being slotted and provided interiorly with two vertical pulleys, and a weighted cord attached to the gate and passing between the adjacent pulleys and through the tube and over the outer pulley, 85 as described.

ABRAM A. STILL.
